ABSTRACT: A pushbutton switch assembly includes a housing having a plurality of movable contacts and a plurality of elongated sliders. The sliders are reciprocably movable to selectively actuate the movable contacts. A plurality of push rods extend from the housing for longitudinal reciprocating movement relative to the housing. The inner ends of the push rods are received in actuating recesses in the sliders for selectively moving the sliders as selected push rods are depressed. A first push rod and its associated actuating recess in a first of the sliders have corresponding generally planar latching surfaces disposed generally perpendicular to the axis of movement of the first push rod for holding that push rod depressed. A second push rod, during depression, engages the first slider to free the first push rod.

**PUSHBUTTON SWITCH ASSEMBLY WITH ACTUATOR
AND SLIDER COMPLEMENTARY LATCH MEANS**

BACKGROUND OF THE INVENTION

In recent years pushbutton switches of the slider type have been widely used in many varied applications such as domestic dishwashers, home laundry appliances, electric ranges, automatic vending machines, etc. to control various circuitry therein. At times it is desirable for a push rod, upon depression, to be releasably retained or secured until some further action takes place. When the push rod is to be released by some external means, such as an electromechanical device, the required releasing force is not critical. One such arrangement is set forth in U.S. Pat. No. 3,322,908, issued to Stewart A. Woodward on May 30, 1967, and assigned to General Electric Company, the assignee of the present invention.

Often it is desired that one push rod, once depressed, be retained until released by depression of another push rod. In such instances any means of push rod retention which requires substantial releasing force is undesirable as it could be vexatious for the user and may lead the user mistakenly to believe the switch has malfunctioned. At the same time the retention of a push rod in its depressed position should be sure. In some such pushbutton switches, the push rods are spring biased to an outer or undepressed position. Also, in some applications one or more of the push rods are also mechanically connected to external devices which exert force on the push rod tending to move it out of its depressed position. One such arrangement is set forth in U.S. Pat. No. 3,384,098, issued to Norman T. Swetnam on May 21, 1968, and assigned to General Electric Company, assignee of the present invention. The push rod retention means should be substantially unaffected by any such forces tending to give undesired release.

SUMMARY OF THE INVENTION

Accordingly it is an object of the present invention to provide an improved pushbutton switch assembly of the slider type.

Another object of the present invention is to provide such an assembly, including improved means for releasably retaining a push rod in its depressed position.

A further object of this invention is to provide such an assembly with a push rod retention means in which a retained push rod is released by depression of another push rod.

A still further object is to provide an improved push rod retention arrangement for use in a pushbutton switch, which arrangement is both sure in operation and released with ease.

In carrying out my invention in one form thereof, I provide an improved pushbutton switch assembly including a housing with a plurality of contact means within the housing. A plurality of elongated sliders are carried by the housing for selective reciprocating movement between first and second positions selectively to actuate the contact means. A plurality of push rod means are mounted to the housing for longitudinal reciprocating movement between extended positions and depressed positions relative to the housing. Each of the push rod means includes an elongated push rod of flat stock having a width sufficient to span all of the sliders. The inner end of each push rod is smoothly curved to form a generally cylindrical actuating portion. There is an actuating recess in each of the elongated sliders to receive the actuating portion of each of the push rod means for selectively moving predetermined ones of the elongated sliders between first and second positions in response to depression of predetermined ones of the push rod means. The generally cylindrical actuating portion associated with one push rod means and one recess in one elongated slider are formed with corresponding generally planar latching surfaces disposed generally perpendicular to the axis of longitudinal reciprocating movement of the one push rod means. The corresponding generally planar latching surfaces are in interfering relationship, when the one push rod means is depressed, for releasably retaining the one push rod means in its depressed position.

BRIEF DESCRIPTION OF THE DRAWING

The subject matter which I regard as my invention is particularly pointed out and distinctly claimed in the concluding portion of the specification. The invention itself, however, together with further objects and advantages thereof, may be best understood by reference to the following description taken in conjunction with the accompanying drawing in which:

10 FIG. 1 is a side elevational view of a multiple pushbutton switch assembly incorporating one embodiment of the present invention;

15 FIG. 2 is a bottom plan view of the switch assembly of FIG. 1, with some parts broken away for illustration;

20 FIG. 3 is a fragmentary layout showing portions of one slider and two associated push rods in accordance with one embodiment of this invention, and illustrating one push rod releasably retained in its depressed position;

25 FIG. 4 is a view similar to FIG. 3 but showing the arrangement of parts just after a retained push rod has been released; and

30 FIG. 5 is a fragmentary side elevational view of another form of push rod useful in the present invention.

DESCRIPTION OF THE PREFERRED EMBODIMENTS

Referring now to the drawing, and initially to FIGS. 1 and 2 thereof, there is shown a pushbutton switch assembly 10 having a hollow housing 11 defining therein an internal cavity 12. Housing 11 may be formed from any suitable material such as a moldable plastic compound to allow the housing to be molded in the desired configuration. The open bottom of the housing 11 is closed by means of a cover plate 13 which is secured in place by means of staking or deforming terminals 14 and 15 at the outer surface of plate 13 and the outer surface of housing 11.

Each of the terminals 14 has a portion 16 bent over to form a support for a stationary contact 17. Similarly, each of the terminals 15 has a blade 18 secured at one end thereto. The blade 18 may be a separate piece secured to terminal 15 by some means such as riveting or staking, or it may be integrally formed with terminal 15. In any event, blade 18 has a relatively fixed end 19 where it joins terminal 15 and a free end 20. A movable contact 21 is secured to blade 18 adjacent the free end 20. Blade 18, at its connection to terminal 15, is given sufficient resiliency so that movable contact 21 is biased into engagement with stationary contact 17 until such time as sufficient force is applied to blade 18 to move contact 21 out of engagement with contact 17. Blade 18 is given a longitudinal bend 22 throughout most of its length to make blade 18 substantially rigid throughout its length, with the flexing action of the movement of the blade 18 being concentrated at fixed end 19.

55 A plurality of elongated sliders 23 are disposed within the cavity 12 and are adapted for reciprocating movement along their longitudinal axis, i.e., toward the right and left as seen in FIGS. 1 and 2. This movement is, of course, transverse to the longitudinal axis of the blades 18. As best seen in FIGS. 3 and 4, the edge of the sliders 23 disposed toward the blades 18 are 60 provided with predetermined high and low sections 24 and 25 respectively. As is well known in the art when a low section 25 of all of the sliders 23 are in line with one of the blades 18, the associated stationary and movable contacts 17 and 21 forming a particular switch will be closed; however, when a high section 24 of one or more of the sliders 23 is brought into alignment with the blade 18, the blade will be moved so as to 65 separate movable contact 21 from stationary contact 17. It will be understood that the positioning of the high and low sections 24 and 25 is varied between the individual sliders 23 so that by selective longitudinal movement of the sliders 23 predetermined ones of the switches formed by the movable and stationary contacts may be caused to open and close.

70 Reciprocating movement of sliders 23 is effected by manual depression of the pushbuttons 26. Each pushbutton is 75 mounted on the distal end of a push rod 27 and 28. Each of the

push rods 27 and 28 is mounted to the housing for longitudinal reciprocating movement between an extended and a depressed position relative to the housing. More particularly, each of the push rods extends through a cooperating opening (not shown) in the upper edge of the housing 11 into the cavity 12 and is disposed for engagement with the other lateral edge of the sliders 23. As is clearly illustrated in FIG. 3, the inner end of each of the push rods 27 and 28 is rolled or formed into a generally cylindrical actuating portion 29. It will be understood that, as it is well known in the art, the push rods 27 and 28 of the exemplification switch assembly are formed from flat metal stock having a width sufficient to span all of the sliders 23 in the cavity 12.

The lateral edges of the sliders 23 opposite the high and low sections 24 and 25 are formed with actuating recesses such as those shown at 30 and 31. Each slider 23 has an actuating recess which is positioned in alignment with the cylindrical actuating portion of each push rod when the sliders and push rods are mounted in the housing. Only actuating recesses 30 and 31 have been shown, for purposes of illustrating the releasable retention of a push rod and its subsequent release, in accordance with one form of the invention. It will be understood that the various actuating recesses in the sliders take many shapes so that depression of any particular push rod will selectively cause one or more sliders to be moved to the right, one or more sliders to be moved to the left, and one or more sliders to remain stationary for selectively closing a predetermined one or more of the switches. The particular configuration adopted for each recess of each slider is generally determined by the switch operation which is desired. As the sliders 23 are moved to the right and left (as seen in FIG. 3) in response to the depression of one of the push rods by manual pressure on its associated pushbutton, a predetermined one or more of the blades 18 are cammed so as to separate the associated stationary movable contacts 17 and 21 while other blades 18 are released for closing its associated contacts, all as is well known in the art.

Referring now particularly to FIG. 3 it will be seen that one edge of recess 30 is formed with a gentle slope, as indicated at 32, while the other edge is formed as an overhanging lip 33. The inner edge of the lip 33 is formed as a generally planar latching surface 34, which is generally perpendicular to the axis of the longitudinal reciprocating movement of the push rod 28. The generally cylindrical actuating portion 29 of the push rod 28 is notched to form a corresponding generally planar latching surface 35 which also is generally perpendicular to the axis of longitudinal reciprocating motion of the push rod 28. The recess 31 is formed on one side with a gently sloping edge 36 and on the other side with a smoothly curved overhanging lip 37. FIG. 3 illustrates the relative position of one of the sliders 23 and the push rod 28 when the push rod 28 is in its depressed position. At this time the generally planar latching surfaces 34 and 35 are disposed in an interfering or overlapping relationship, thus any force tending to move the push rod 28 longitudinally outward of the housing, i.e., upward in FIG. 3 causes the surfaces 34 and 35 to engage. This prevents such outward movement of the push rod 28.

Such a force with the exemplification switch normally would be exerted on the push rod 28 by means of an external element attached to the push rod. Push rod 28 is adapted for such attachment by means of a notch 38 formed in the push rod intermediate its ends. Thus the exemplification switch is well adapted for use in a device such as the automatic dishwasher set forth in the aforementioned U.S. Pat. No. 3,384,098, wherein one of the push rods of a multiple pushbutton switch is mechanically connected by flexible arm to a valve so that, upon depression of that particular push rod to select a gentle wash cycle for instance, the valve is opened to admit air to the pump of the dishwasher and thus reduce the velocity of the water spray. In such an arrangement the arm interconnecting the valve and the push rod exerts a force on the push rod tending to move it to its outward position relative to the switch housing. The push rod must be releasably retained

in its depressed position at least until the end of the gentle wash cycle.

Referring now to FIG. 4 there is illustrated the relative positions between the elements shown in FIG. 3 as the illustrated push rod 27 is depressed. This action changes the settings of the stationary and movable contacts and releases push rod 28. As the push rod 27 moves from its outer or extended position toward its inner or depressed position, its generally cylindrical actuating portion 29 engages the smoothly curved lip 37. This engagement of the actuating portion of the push rod 27 with the lip 37 moves the slider 23 to the left (as seen in FIG. 4) which in turn moves the latching surface 34 out of its interfering relationship with latching surface 35. This frees the push rod 28 for movement to its extended position. It will be noted that the inner portion of recess 30 is sufficiently wide to allow this relative movement between the slider 23 and push rod 28 without binding. It will be understood that the recess 31 well could be formed with a different configuration to provide the same releasing action. For instance, the gently sloping edge 36 could be provided on the left-hand side of the recess 31 and extend generally from the left to the right between the outer edge of the slider and the interior portion of the slider in the event it is intended for the depression of push rod 27 to cause the slider to move and remain to the left.

FIG. 5 illustrates another form of push rod which may be releasably retained by a slider such as that illustrated in FIGS. 3 and 4. To this end the inner end of slider 28a is curved into a generally cylindrical actuating portion 29a. However, the actuating portion 29a does not fold back on itself. Rather it terminates in a generally planar latching surface 35a which is disposed generally perpendicular to the axis of longitudinal movement of the slider 28a. Such a slider 28a will provide the same releasable retention or latching function of the slider 28.

While in accordance with the Patent Statutes I have described what at present are considered to be the preferred embodiments of my invention, it will be obvious to those skilled in the art that numerous changes and modifications may be made therein without departing from the invention, it is therefore aimed in the appended claims to cover all such equivalent variations as fall within the true spirit and scope of the invention.

What I claim as new and desire to secure by Letters Patent of the United States is:

1. An improved pushbutton switch assembly including: a housing; a plurality of contact means in said housing; a plurality of elongated sliders carried by said housing for selective reciprocating movement between first and second positions selectively to actuate said contact means; a plurality of push rod means mounted to said housing for longitudinal reciprocating movement between extended positions and depressed positions relative to said housing; each of said push rod means including an elongated push rod of flat stock having a width sufficient to span all of said sliders; the inner end of each push rod being smoothly curved to form a generally cylindrical actuating portion; a plurality of actuating recesses in each of said plurality of elongated sliders, there being a recess in each of said plurality of elongated sliders to receive said actuating portion of each of said push rod means for selectively moving predetermined ones of said elongated sliders between first and second positions in response to depression of predetermined ones of said push rod means; said generally cylindrical actuating portion associated with a first push rod means and a first recess in a first elongated slider being formed with corresponding generally planar latching surfaces disposed generally perpendicular to the axis of longitudinal reciprocating movement of said first push rod means; said corresponding generally planar latching surfaces being disposed in interfering relationship, when said first push rod means is depressed, for releasably retaining said first push rod means in its depressed position.
2. A pushbutton switch assembly as set forth in claim 1 wherein said one generally planar latching surface is provided by a notch in the periphery of said slider actuating portion.

3. A pushbutton switch assembly as set forth in claim 1 wherein: said generally cylindrical slider actuating portion of said first push rod means is formed with its distal edge disposed generally perpendicularly to the axis of longitudinal reciprocating movement of said first push rod means for forming one of said planar latching surfaces.

4. A pushbutton switch assembly as set forth in claim 1

wherein: said actuating portion of at least a second push rod means, during movement from its extended position to its depressed position when said first push rod means is in its depressed position, engages said first elongated slider for causing relative movement between said planar latching surfaces to release said actuating portion of said first push rod means.
